New York, N. Y., a corporation of Delaware

Application April 10, 1943, Serial No. 482,525

14 Claims. (Cl. 175—362)

1

This invention relates to transformers and particularly to transformer windings adapted for improved operation when carrying substantial currents.

A principal purpose is to provide a substantially lighter transformer construction, the preferred form being especially suitable for use in aircraft in which reduced weight is of primary importance. Further purposes are to improve heat radiation from the winding, to reduce materially the copper loss, and the provision of an improved supporting bracket structure.

Other objects and advantages will appear from the following description considered in connection with the accompanying drawings, in which

Fig. 1 is a side elevation of a transformer embodying the invention;

Fig. 2 is a plan view thereof;

Fig. 3 is a vertical section through a winding on line 3—3 of Fig. 2;

Fig. 4 is a vertical section on line 4—4 of Fig. 2; and

Fig. 5 is an enlarged fragmentary view of an end of the coil.

The invention is illustrated in connection with a step-down transformer having three coils C mounted on a core A formed of two E type halves suitably held together, as by a metal clamping band 10 fastened by clips 11. Suitable mounting brackets are provided, and an improved construction is shown which gives the necessary solidity of support with a minimum of weight, together with ease of assembly. In this arrangement four brackets 12 are provided, each extending transversely across a corner of the core A and being constructed of metal angle sections having suitable mounting lugs 12a soldered to the end portions of each bracket. The brackets 12 are all held firmly in place on the core A by a clamping band 13 of suitable metal such as steel which is placed under tension and held in position by clip 14, said band and clip being advantageously similar to those customarily employed in fastening cases and the like. The band is advantageously stretched to a point below its elastic limit, permitting expansion and contraction without deformation or loss of tension.

Each bracket 12 is advantageously provided with inwardly extending retaining lugs 12b attached as by soldering to the inner edges of the bracket and arranged to bear against the adjacent opposite faces of the core A to prevent endwise movement of the core. Where the bracket is made of aluminum, an aluminum alloy such as duralumin, or other metal that might have an

2

objectionable reaction with the iron of the core, suitable insulation such as a sheet of glass cloth 12c may be interposed between each bracket 12 and the adjacent portion of the core A.

The coils C are identical in construction, so only one coil will be described. It is mounted on winding tube 15 of usual type, held in place on the core A by wedges W which may be formed from suitable insulating material. The coil comprises an inner primary winding of rectangular copper wire, the successive layers 16 of the wire and adjacent turns of the wire being suitably insulated. For this purpose the wire may be covered with glass fabric or other insulation, and successive layers of the winding may be separated by insulating strips of wire cloth, located in the portions of the successive layers of the winding that bear against each other, and preferably omitted in the portions that are spaced from each other as hereinafter set forth. In the illustrated embodiment there are five layers 16 in the primary winding.

The secondary winding consists of a plurality of turns formed from a strip of sheet metal which ordinarily will be equal in width to the primary layers 16, and which preferably is formed from extremely thin sheet metal such as copper, a strip of 0.0216 inch thick and 2½ inches wide having been used effectively in a transformer embodying the invention. The portions of successive turns 18 which lie against each other are separated by suitable insulation, which may advantageously consist of glass cloth strips 17. In the form illustrated the secondary winding consists of six turns.

The transformer is designed to carry relatively high current, especially in the secondary, which necessarily results in a substantial tendency toward heating. In order to improve the radiation of heat from the windings, the portions thereof located at opposite sides of the core A are provided with air ducts 20 extending between adjacent layers 16 of the primary and between turns 18 of the secondary. Each duct 20 is formed by the insertion of spacers 21 extending parallel to the winding axis and advantageously located adjacent the ends of the straight runs of said layers and turns that lie parallel to the sides of the core A. Spacers 21 are formed of suitable material having necessary insulating, mechanical and dielectric properties. For this purpose a material made up of superposed sheets of glass cloth consolidated by a binder which is highly resistant to temperature changes has been found especially suitable, a commercial form of this material being designated by the trade-mark FT-10 (Formica).

However, the spacer 24a which overlies the commencement of the secondary strip winding, and spacer 21b which rests against the outer end of the secondary strip, may be formed of conducting material, preferably a metal such as copper, and may be soldered to the subjacent end portions of the secondary winding.

The given number of air ducts 28 for any number of turns or layers of the winding may be varied in order to balance the improved cooling effect against the added bulk and labor involved in providing additional ducts. In the form illustrated a duct is provided after every other layer 18 of the primary winding, and after every third turn 18 of the secondary; but this may be varied in accordance with the requirements of different designs, and every turn may be spaced from adjacent turns by air ducts if desired.

To facilitate the assembly of the duct spacers and the winding of conductors thereon, clamping bolts 22 are provided, each extending through the winding tube 15 and the aligned ends of each set of spacers 21 projecting beyond the winding, spacing washers 23 being placed on each bolt 22 between the duct spacers 21 and serving to maintain the latter in proper spaced position.

In order to prevent any tendency to vibrate or flutter that the portions of the secondary winding located between adjacent air ducts 28 might have under the stresses introduced by the currents flowing through them or the action of air under pressure passing into and through said ducts, the secondary winding is applied under relatively high tension, much greater than that ordinarily used in winding transformers, so that the tension of the portions of the turns 18 between spacers 21 is sufficient to prevent appreciable fluttering or vibration. The tension is maintained by virtue of the fact that the ends of the secondary strip are soldered to the spacers 21a and 21b, as already described. A tension in excess of five hundred pounds, and which may be in the neighborhood of 700 pounds, applied to a secondary strip of the dimensions indicated above, has been found suitable. This tension likewise permits the provision of air ducts 28 which are of substantial width in a direction transverse to the coil axis, thereby increasing materially the surface area of the secondary turns 18 which can be exposed to the cooling air. With this arrangement the portions of said secondary turns on opposite sides of the air ducts 28 are substantially flat and parallel, and will remain in this condition during transformer use. Such ducts as shown may extend across substantially the entire width of one side of the coil.

The terminals of the primary winding are brought out and connected as desired in the usual manner. The ends of the secondary winding are provided with suitable connecting leads. In the form illustrated the ends 19 of each secondary winding strip are bent diagonally so that they project beyond the coil and may be readily connected to leads. They are shown as connected in delta by bus bars 24 extending across the ends of the windings, each having a terminal strip 25 clamped to it and extending outwardly into suitable position for attaching leads.

An arrangement is advantageously provided for forcing air through the ducts 28 at a velocity sufficient to maintain the transformer windings at suitable temperatures even when carrying very high current loads. In the form illustrated the transformer is enclosed in a housing 26 forming an air passage extending parallel to the axes of

the transformer coils and spaced from the outer face of the coils by a short distance which may be substantially the same as the radial width of air ducts 28. The transformer is advantageously mounted on housing 26 as by screws 27 passing through hugs 28a.

Suitable means may be provided for forcing air under pressure through housing 26, the air passing through air ducts 28 and around the exposed faces of the transformer coils. Where the transformer is mounted in aircraft the air pressure may be provided by connecting an end of housing 26 to the air stream outside of the aircraft, preferably in the slip stream of one of the propellers; but of course the same result may be accomplished by providing a source of air pressure, such as a fan or blower B.

The air velocity will be determined by the air temperature and the heat generated in the transformer, as well as by the radial width of air ducts 28. It is advantageous to provide a turbulent flow of the air through ducts 28 thereby increasing the cooling efficiency of the air, an important factor where the radial thickness of the ducts should be kept at a minimum. It has been found that turbulence will exist when the velocity of air through a passage such as a duct 28 exceeds a critical velocity. It has been found that the air flow obtained by connection of housing 26 with the air stream outside of aircraft in flight is adequate for the cooling of transformers of the indicated type, and will produce the desired type of flow. In fact, with air pressure of this type it has been found practical to employ sufficiently narrow air ducts 28 to permit a relatively compact transformer design while maintaining the necessary cooling action. For instance, it has been found practicable to employ air ducts having a radial diameter of about $\frac{1}{8}$ inch, the temperature of the transformer being maintained at a satisfactory point by using air under a pressure of .035 pound per square inch producing a velocity of 750 feet per minute, when a current of 390 amperes is flowing in the secondary winding specifically described above. Under these conditions the temperature of the secondary winding remains below 130° F.

Transformers embodying this invention are substantially lighter than transformers heretofore provided for similar service. The use of thin sheet metal for the secondary winding has the double advantage of reducing very substantially the copper loss and of improving materially the rate of heat radiation. For instance, in a typical transformer embodying the invention operating at 1,000 cycles, the secondary winding has a copper loss of about 650 watts, whereas a winding with the same number of turns of square wire having the same cross-sectional area and arranged in one layer has a copper loss of 4,000 watts. With reference to cooling, the sheet metal strip having the dimensions set forth has a surface area of 5.8 square inches per inch of conductor length, while the corresponding square wire has a surface of only 1.03 square inches. A nine turn coil having a mean length per turn of 12 inches when made with a sheet metal winding has a radiating surface about nine times as great as that of a similar coil wound from square wire of the same cross-sectional area. Nearly all of the surface area of the sheet metal strip is moreover located at the sides where it can be exposed to cooling air, whereas only half of the square wire surface can be thus exposed.

The bracket construction and mounting is sub-

stantially simpler than prior arrangements in which the brackets were attached to the core by bolts, screws or the like. With the arrangement disclosed all of the brackets can be simultaneously mounted on the core; the number of brackets and their location can be varied without affecting the core construction; and the portion of the core which serves as a path for the magnetic flux is not interrupted or affected by bolts, screws or other projections made of metal having entirely different characteristics. When the brackets are made of a metal which might interact chemically or otherwise with the registering portions of the core, particularly when moisture is present, the disclosed type of mounting is furthermore advantageous since it facilitates the use of a simple insulating element between each bracket and the core, made of material which is suitable for the prevention of any such electrolytic or other action, an arrangement that is difficult to provide where the brackets are attached by the usual fastening means.

While a specific embodiment of the invention has been disclosed, this is intended to be illustrative rather than restrictive, the scope of the invention being indicated in the claims.

What is claimed is:

1. A transformer construction comprising a core, cooperating induction coils mounted on said core, a bracket construction for supporting said core bearing against the core, and a retaining band extending around the bracket construction and core under tension, arranged to hold said core in place against said bracket construction.

2. A transformer construction as set forth in claim 1, in which the band is formed of metal and is under tension below its elastic limit, arranged to permit expansion of the core and stretching of the band without permanent deformation of said band.

3. A transformer construction comprising a generally flat core, induction coils mounted on said core, a bracket for supporting the core extending transversely thereto, means for clamping the bracket against the surface of the core, and retaining means on the bracket engaging opposite sides of the core arranged to prevent movement of the core with respect to the bracket.

4. A transformer construction comprising a core of ferrous metal, induction coils mounted on said core, a supporting bracket of non-ferrous metal, an insulating element located between the bracket and the core, and strap means for holding the core in position on the bracket bearing against said insulating element.

5. In a transformer coil construction, a winding tube, a plurality of winding layers formed of a strip of thin sheet metal wound around said tube with the width of the strip extending lengthwise of the tube, and a plurality of spacing members extending lengthwise of said tube between contiguous winding layers with at least some of the spacing members being formed of insulating material and with the spacing members forming an open-ended cooling air-duct intermediate the spacing members and between the flat surfaces of the winding layers, and with the sheet metal being bent around a portion of the spacing members at the edges of the air-duct thereby to assist in maintaining tension on the sheet metal at the air-duct.

6. In a transformer coil construction, a winding tube, a plurality of winding layers formed of a strip of thin sheet metal wound around said tube with the width of the strip extending length-

wise of the tube, and a plurality of spacing members extending lengthwise of said tube between contiguous winding layers with at least some of the spacing members being formed of conducting material and forming lead-in conductors for the winding layers and extending lengthwise through the length of the coil and with the spacing members forming open-ended cooling air-ducts intermediate the spacing members and between the flat surfaces of the sheet metal.

7. A transformer coil construction comprising, a winding tube, a plurality of winding layers formed of a strip of substantially flat conducting material wound around said tube and extending lengthwise thereof, a plurality of spacing members positioned in two groups which groups are spaced arcuately with respect to the central axis of the tube with the spacing members in each group being parallel to each other and radially disposed with the ends of the spacing members projecting beyond the ends of the coil and with each spacing member being positioned between contiguous winding layers, the two groups of spacing members thus cooperating to form a plurality of parallel open-ended cooling ducts, and a plurality of clamping devices mounted on said winding tube and each engaging the adjacent ends of one group of the spacing members whereby the spacing members are held in rigid fixed relationship.

8. In a transformer construction, the combination of, a winding form, a plurality of winding layers formed of a strip of substantially flat conducting material wound around said form and extending lengthwise thereof, a plurality of spacing members positioned in two groups which groups are spaced arcuately with respect to the central axis of the winding form with the spacing members in each group being parallel to each other and radially disposed with respect to said axis and with each spacing member being positioned between contiguous winding layers, the two groups of spacing members thus cooperating to form a plurality of parallel open-ended cooling ducts, and insulating means separating said winding layers in zones arcuately spaced from said air-ducts with the strip of conducting material being secured at its ends and held taut throughout by the cooperative action of friction on the strip by said spacing members and said insulating means.

9. In a transformer construction, the combination of, a core having a leg, a winding form on said leg of rectangular cross section, a plurality of winding layers formed of a strip of conducting material wound around said form with each winding layer having two pairs of parallel sides which extend along the respective sides of said form, a plurality of spacing members positioned in four groups which are positioned respectively at the four corners of the form with the spacing members in each group being parallel to each other and in alignment with the zone of intersection of the sides of the winding layers and with each spacing member being positioned between contiguous winding layers, the spacing members being so disposed that with the winding layers stretched tightly around them a plurality of parallel open-ended cooling ducts are formed, said contiguous winding layers forming air ducts along two opposite sides of the winding form while the winding layers are held in close proximity along the other two sides, and insulating means between the winding layers along said other two sides.

10. In a transformer, the combination of, a core

construction having a leg with an adjacent opening; and a winding assembly comprising, insulating means surrounding said leg, a coil assembly formed by a plurality of winding layers wound around said leg with the layers insulated from each other by said insulating means only through said opening and with the layers being spaced from each other thereby to provide open ducts between the layers exteriorly of said winding space, a plurality of elongated rigid spacing members mounted in fixed parallel relationship parallel to and spaced from said leg each spacing member being between contiguous winding layers thereby to maintain the layers in said spaced relationship.

11. In a polyphase transformer, the combination of, a core construction having three parallel legs with winding space between the legs, a winding assembly including a winding wound on each of said legs, each of the windings being formed by single-turn layers formed by a strip of thin sheet metal the width of which is equal to the length of the coils, and a plurality of spacing members holding the layers of said windings in taut spaced condition with the two ends of each winding secured to the adjacent spacing members and with said adjacent spacing members providing the electrical connections to the windings.

12. In a three-phase transformer, the combination of, a core built up of E-shaped laminations and having three legs with two openings between the legs, a strip of sheet metal holding said core in fixed relationship, a winding assembly formed by primary and secondary windings on each of said legs, certain of said windings being formed by strips of sheet metal wound tightly and held taut, a plurality of spacing members positioned in spaced relationship between the layers of said windings and holding said windings separated exteriorly of said openings between said legs whereby air ducts are provided, and insulation means filling the space between the layers of the winding within said openings.

13. In a transformer, the combination of, a core having a plurality of legs separated by an opening; and a winding assembly comprising, a winding shell surrounding one of said legs and extending through said opening adjacent said leg with the axis of the shell concentric with the axis

of the leg, a pair of radially disposed parallel posts rigidly carried by said shell and spaced axially with respect to the axis of the leg, and a plurality of spacers carried by said posts in fixed parallel relationship and adapted to hold the layers of the coil in predetermined fixed relationship whereby air ducts are provided between the coil layers.

14. In an air-cooled transformer construction, the combination of, a core assembly having an opening therein; and a winding assembly including, a plurality of winding layers extending through said opening, and a plurality of insulating layers positioned within said opening intermediate the winding layers and forming with the winding layers a compact assembly, said winding assembly including a plurality of insulating members positioned outside said opening and holding said winding layers in rigid spaced relationship thereby forming air ducts between the winding layers with the winding layers being held taut by the cooperative action of the insulating layers within said opening and the insulating members.
